COMBINATION ASH TRAY AND BRIDGE SCORE PAD HOLDER

Frank Howard Mellon, Pittsburgh, Pa.

Application February 26, 1932. Serial No. 595,376

3 Claims. (Cl. 281—44)

The present invention relates to a combination ash tray and bridge score pad holder and primarily to the pad holder and the object of the invention resides in the provision of a score pad holder so constructed that it may always be visible to all of the participants in a bridge game and may be manipulated so as to be conveniently written upon at the time the scores are to be noted.

Another very important object of the invention resides in the provision of a device of this nature which is exceedingly simple in its construction, inexpensive to manufacture, strong and durable, thoroughly efficient and reliable in use and operation, compact and convenient, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawings:

Figure 1 is a side elevation of the device embodying the features of my invention.

Figure 2 is a top plan view thereof.

Figure 3 is a fragmentary longitudinal vertical section therethrough.

Figure 4 is a detail section taken substantially on the line 4—4 of Figure 2.

Figure 5 is an end elevation of the plate.

Figure 6 is a horizontal section taken substantially on the line 6—6 of Figure 3, and

Figure 7 is a fragmentary bottom plan view of the base, the nut and washer of the spindle being removed.

Referring to the drawings in detail it will be seen that the numeral 5 denotes a plate preferably constructed of metal and revolvably mounted on a base 6 also preferably of metal and also preferably fashioned to make an ash receptacle. The plate 5 revolves by being attached or mounted on a spindle 7 extending into a suitable opening 8 in the base 6 and a spring 9 is coiled about the spindle within the opening and has one end anchored in the base and the other end anchored in the spindle so as to return the spindle and the plate 5 to a predetermined position. The plate 5 is in a plane oblique to the axis of the spindle 7. This revolving plate is grooved on one edge as indicated at 10 to hold the scoring pencil and a suitable device 11 is mounted at the upper end of the plate to securely attach a score pad thereto.

This device is placed to the left of the scorekeeper with the plate holding the score pad facing the center of the table. When the scorekeeper

wishes to enter the score on the pad, he turns the plate 5 toward him and when through with his notation the spring automatically returns the plate to the aforementioned or original position.

It is thought that the construction, operation, utility and advantages of this device will now be clearly understood to those skilled in this art without a more detailed description.

The present embodiment of the invention has been described in considerable detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

1. A device of the character described comprising a base having a vertical opening therethrough a portion of which constitutes a journal bearing, said opening having an enlarged portion at its lower end defining with the remainder of the opening a shoulder, an inclined rotatable table, a shaft depending from the table and journaled in the said opening and having a reduced threaded portion located below the said shoulder and defining a shoulder on the shaft on a level with said shoulder in the said opening, a washer in the enlarged portion of the opening and engaged with the shoulder in the opening and provided with an opening through which the reduced threaded portion of the shaft is received in a manner to engage the washer also with the shoulder on the shaft, and a nut threaded on the reduced threaded portion of the shaft below and engaging the washer for preventing relative longitudinal movement of said shaft in said opening in the base.

2. A device of the character described comprising a base having a vertical opening therethrough a portion of which constitutes a journal bearing, said opening having an enlarged portion at its lower end defining with the remainder of the opening a shoulder, an inclined rotatable table, a shaft depending from the table and journaled in the said opening and having a reduced threaded portion located below the said shoulder and defining a shoulder on the shaft on a level with said shoulder in the said opening, a washer in the enlarged portion of the opening and engaged with

the shoulder in the opening and provided with an opening through which the reduced threaded portion of the shaft is received in a manner to engage the washer also with the shoulder on the shaft, and a nut threaded on the reduced threaded portion of the shaft below and engaging the washer for preventing relative longitudinal movement of said shaft in said opening in the base, said shaft having a second shoulder rotatably engaged with the base around the upper end of the opening in the base.

3. A device of the character described comprising a base having a vertical opening therethrough a portion of which constitutes a journal bearing, said opening having an enlarged portion at its lower end defining with the remainder of the opening a shoulder, an inclined rotatable table, a shaft depending from the table and journaled in the said opening and having a reduced threaded portion located below the said shoulder and defining a shoulder on the shaft on a level with said shoulder in the said opening, a washer in the enlarged portion of the opening and engaged with

the shoulder in the opening and provided with an opening through which the reduced threaded portion of the shaft is received in a manner to engage the washer also with the shoulder on the shaft, and a nut threaded on the reduced threaded portion of the shaft below and engaging the washer for preventing relative longitudinal movement of said shaft in said opening in the base, said shaft having a second shoulder rotatably engaged with the base around the upper end of the opening in the base, and a helical spring composed on the shaft between the second shoulder and the first-mentioned shoulder on the shaft and having its upper end anchored in the shaft and its lower end outwardly directed and engaged in a recess in the said shoulder of the opening having a portion opening through the lower surface of the last-mentioned shoulder whereby said washer may act as a closure to retain the lower end of the spring in the recess, said spring being adapted to return to the table to initial position after rotation thereof.
